UNITED STATES PATENT OFFICE.

HERMAN PRIES, OF MICHIGAN CITY, INDIANA.

UNDERFRAMING FOR CARS.

No. 893,650.

Specification of Letters Patent.

Patented July 21, 1908.

Application filed January 6, 1908. Serial No. 409,496.

To all whom it may concern:

Be it known that I, HERMAN PRIES, a citizen of the United States, and resident of Michigan City, county of LaPorte, and State 5 of Indiana, have invented certain new and useful Improvements in Underframing for Cars, of which the following is a specification, and which are illustrated in the accompanying drawings, forming a part thereof.

10 This invention relates to underframing for freight cars of various types, and is applicable to structures in which either metal or wood sills are used.

15 The object of the invention is to secure both great strength and simplicity, and to generally improve on the art as now practiced.

20 The invention consists in the structure hereinafter described, and which is illustrated in the accompanying drawings, in which

Figure 1 is a detail side view of the underframing of a car, some portions being omitted and others being broken away, and some 25 parts being shown in cross section; Fig. 2 is a detail plan view of the bottom of a car, some portions being broken away and parts of the structure being omitted; Fig. 3 is a cross-section of the bottom of a car showing 30 one of the body bolsters in elevation; Fig. 4 is a cross-section of the bottom of a car showing one of the cross-ties in elevation; Figs. 5 and 6 are detail cross-sections of a car bottom showing a portion of the body bolster in 35 elevation and illustrating modified forms of construction; Fig. 7 is a detail longitudinal section of the bottom of a car showing the body bolster in cross-section.

The floor of a car is represented at 10 and 40 its end sills at 11 and 12, the usual truss-rods 13 extending longitudinally of the car and uniting the end sills.

In the preferred form of construction the longitudinal sills are of metal and have the 45 form of channel beams; the center sills being shown at 14, 15, the side sills at 16, 17, and the intermediate sills at 18, 19. The center sills 14, 15, are of greater vertical width than the side and intermediate sills, and their 50 upper faces are spaced apart from the bottom of the floor 10, while the upper faces of the side and intermediate sills are preferably in contact therewith. Nailing strips 20, 21, are interposed between the center sills and 55 the car floor, and nailing strips 22, 23 and 24, 25, lie adjacent, respectively, to the side

and center sills and rest upon brackets 26, 27 and 28, 29 secured thereto.

The body bolsters are sectional in form, and the center sills are incorporated into them. Each of these body bolsters comprises two end sections, each formed of a pair of flanged plates 30, 31, preferably, though not necessarily, of cast metal. These plates form the vertical sides of the end section of the bolster. At their inner ends are outwardly - turned flanges 32, 33, which lie against and are riveted to the outer face of the center sill, as 14 (see Fig. 7).

The vertical width of the inner ends of the 70 plates 30, 31, is the same as that of the center sills. Their upper faces are offset downwardly to accommodate the intermediate and side sills, as plainly shown in Fig. 3, the offset forming shoulders 34, 35, against which 75 the inner faces of the intermediate sills 18, 19, take bearings. The plates 30, 31, have outwardly - directed top flanges 36, 37, throughout their lengths, to which flanges the side and intermediate sills are riveted, 80 as shown at 38, 39. A tension member 40, considering the body bolster as a truss, in the form of a plate rests upon and is riveted to the top flanges 36, 37, extending between the shoulders 34, 35.

The bottoms of the two bolster sections 30, 31, incline upwardly towards their outer ends, and are provided with inturned flanges 41, 42, to which is applied and riveted the compression truss member 43, in the form of 85 a plate, the length of this plate being optional with the builder, preferably being somewhat less than the extreme length of the bolster, as shown in Fig. 3.

By reason of the described arrangement of 90 top and bottom bolster flanges, the tension member 40 is of greater width than the compression member 43, thus providing the maximum strength where most requisite, the compression member being reinforced by a 95 pair of filling plates 44, only one of which is shown in the drawings, located between the center sills, in line with the side plates 30, 31, and having outstanding vertical flanges 45, 46, secured to the sills by the same rivets 47 100 which secure the end flanges of the plates 30, 31, thereto.

The usual center plate 47 is secured to the bottom of the bolster for engaging the center plate 48 of the truck bolster.

Side bearing plates 49, 50, are secured to 110 the lower face of the body bolster, and chairs

51, 52, 53, 54, are secured to the upper face of the body bolster to carry the truss-rods 13.

In flat or gondola car construction the outer end of the bolster takes the form shown in Fig. 5, being offset downwardly, as shown at 55, to form a seat for the side sill 56 to bring the outer face thereof flush with the side edge of the floor 10, a nailing strip 57 being in this case mounted upon the top of the side sill and a stake bracket 58 being attached to the outer face of the sill.

The cross-ties 59, 60, located between the two body bolsters, are in the form of straight I-beams, and are riveted to the lower faces of the center sills, as shown at 61, 62, Fig. 4, and are of less length than the width of the car bottom. Chairs 63, 64, rest upon and are riveted to the cross-ties adjacent their ends, and support and are riveted to the side and intermediate sills, these chairs being in the form of flanged plates and being prolonged outwardly beyond the ends of the cross-ties for engagement with the side sills.

This construction of the cross-ties and their accessories, while insuring ample strength, provides side clearance for the car frame, thus lessening the danger of injury to the structure by extraneous objects. The usual struts 65, 66, for the truss-rods 13 depend from and are secured to the cross-ties.

In the construction illustrated in Fig. 6, the side sills 67 and intermediate sills 68 are of wood and directly support the car floor 10, supplemental nailing strips not being required.

I claim as my invention—

1. In an underframing for cars, in combination, a pair of center sills, a cross-tie of less length than the car frame and secured to the under faces of the center sills, a chair mounted upon each end of the cross-tie and projecting upwardly and outwardly, and side and intermediate sills resting upon such chairs.

2. In an underframing for cars, in combination, a pair of center sills, bolster sections 45 projecting laterally from the outer faces of the center sills and each comprising a pair of plates having their upper edges flanged outward and their lower edges flanged inward, tension and compression plates uniting the 50 bolster sections and being secured, respectively, to their outturned and to their inturned flanges.

3. In an underframing for cars, in combination, a pair of center sills, bolster sections 55 projecting laterally from the outer faces of the center sills and each comprising a pair of vertically-disposed plates having the outer portions of their upper edges offset downwardly and the inner portions thereof outwardly flanged and having their lower edges inwardly flanged, tension and compression plates uniting the bolster sections and being secured, respectively, to their outturned and their inturned flanges, and outer sills resting 60 upon the offset portions of the bolster sections.

4. In an underframing for cars, in combination, a pair of center sills, bolster sections 70 projecting laterally from the outer faces of the center sills and each comprising a pair of vertically-disposed plates having the outer portions of their upper edges offset downwardly and the inner portions thereof outwardly flanged and having their lower edges 75 inwardly flanged, tension and compression plates uniting the bolster sections and being secured, respectively, to their outturned and their inturned flanges, and outer sills resting 80 upon the offset portions of the bolster sections and extending above the center sills.

HERMAN PRIES.
